UNITED STATES PATENT OFFICE.

ROBERT B. GRIFFIN, OF NEW YORK, N. Y.

DESIGN FOR WALL-COVERING.

48,518.

Specification for Design.

Patented Feb. 8, 1916.

Application filed October 19, 1915. Serial No. 56,812. Term of patent 7 years.

To all whom it may concern:

Be it known that I, ROBERT B. GRIFFIN, a citizen of the United States, residing at New York, county of New York, State of New York, have invented a new, original, and ornamental Design for a Wall-Covering, of which the following is a specification, reference being had to the accompanying drawing, forming a part thereof.

The drawing is a plan view of a wall covering embodying my design.

What I claim is:

The ornamental design for wall covering, substantially as shown.

ROBERT B. GRIFFIN.

Witnesses:

F. W. SCHAEFER,
A. KARFAY.
